J. Henry. Lawson of Boston. Mass.

Letters Patent

The Schedule referred to in these Letters Patent, and making part of the same, containing a description in the words of the said Henry Lawson, himself of his improvement in the Machinery for raising, or winding up window shades, curtains, &c &c.

To all to whom these presents shall come,
Be it known, that J. Henry Lawson of Boston, in the County of
Suffolk, and state of Massachusetts, have invented a new
and useful improvement in the Machinery for winding
up window shades, or curtains, &c &c &c. and the following
is a full and exact description of the construction and
operation of the said Machinery, as invented or improved
by me. To one end of the roller, on which the cloth is
wound there is a barrel bounded by two flanges, to which
barrel the cord is made fast and wound round as the roller
revolves and the cloth runs off the roller.

The diameter of this barrel is made small, that it may
take up but little cord as it revolves, and the diameter of the
axis is made greater than that of the barrel to aid in check-
ing the force, or velocity of the cloth to in running off the roller.
The cord is then passed through the pendant balance pulley
B, and carried back to any convenient distance C, and
there made fast. The pendant balance pulley may be made
of any convenient form and must be of sufficient weight
to counterpoise the cloth &c. on the roller and so con-
structed that the cord cannot get off the sheave or sheaves
therein. The use of this pendant balance pulley is to
keep the cord tight on the barrel and prevent its run-
ning

running over the flanges, to check the cloth so as to run off the roller and to stop it when required also by the man in which it is suspended to shorten the fall of the slack cord as it runs off the barrel and enable you to roll up the whole of the cloth so, at one economical hand pull, to serve as a handle, a pull at which will wind the whole of the cloth on the roller, when it is required to roll up an excessive length of cloth say about 13 ft long it will be necessary to have two sheers in the balance making it a double pulley. My claim is, 1st for reducing the length of the drum (required to roll up any species of roller blind, shade, curtain, mat, &c. of any required length) to a convenient hand pull that is by one easy move of the hand to cause the roller to revolve sufficiently to wind up any length of cloth so required for the above purposes in the manner as above described. 2nd for the pulley balance pulley and the manner of applying it as above described. 3rd for the relative proportions of the barrel & wire as above described.
